United States Patent Office.

WILLIAM H. T. TOMLIN, OF MULLICA HILL, NEW JERSEY.

Letters Patent No. 64,167, dated April 23, 1867.

IMPROVEMENT IN HORSE HAY-FORKS.

The Schedule referred to in these Letters Patent and making part of the same.

TO ALL WHOM IT MAY CONCERN:

Be it known that I, W. H. T. TOMLIN, of Mullica Hill, in the county of Gloucester, and State of New Jersey, have invented certain new and useful Improvements in Hay-Elevators; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in constructing a new and improved hay-elevator in a novel manner.

Figure 1 represents a longitudinal vertical view on the line z x of fig. 2.

Figure 2 represents a side view.

I construct my hay-elevator by making a standard, A, and framing on to its lower end a cross-beam, B. The cross-beam B I render strong and firm by the braces a a of fig. 2. In the standard A, I make a slot or opening, b , having smaller slots or grooves on each side, as shown in fig. 1. To the lower side of the cross-beam B, I fasten two arms c c , as shown in both figures. These arms I extend to an equal distance on either side of the cross-beam B, and at right angles to it. On the ends of these arms c c , I hinge the beams or head-pieces C C having curved tines d d d d in fig. 1 and fig. 2, at the points e e in fig. 1. In the slot b of the standard A, I connect two levers f g , by a toggle-joint, h , fig. 1. These levers f g I hinge on to the arms i j at the points k l , fig. 1. The arms i j are rigidly attached to the beams or head-pieces C C, as shown in fig. 2. The pivots o connecting the levers f g at the toggle-joint h , I make long enough to run in the grooves t on either side of the slot b in the standard A, and also to form a loop over the top of the joint, as shown in fig. 2. To this loop I attach a cord, m , and pass it up through the standard and out at its side over the sheave or pulley n . The standard has a hole bored in it for the purpose of letting the cord through. The pulley n I fasten or suspend from the top of the standard A. At the top of the standard I have a loop or eye, o , as shown in both figures.

In operating my hay-elevator I employ blocks, tackle, and rope in the ordinary way. I fasten a tackle-block to an upper beam or rafter in the barn. Attaching a rope to the upper end of the standard A, I pass it through the block in the barn, then through another block near the ground, if necessary. By pulling on the cord m I open or spread the tines d d d d and drop the elevator on to the hay to be raised. Then I press down the levers f g at the toggle-joint h till they are in a line. In doing this I cause the tines to grasp the hay and hold it. Then by means of the rope and tackle I elevate the whole into the barn, and release the hay by pulling on the cord m and spreading the tines. This operation I repeat as often as desired. It is obvious that my elevator may be used to elevate grain or corn-stalks as well.

Having thus described my invention, what I claim, is—

A hay-elevator consisting of the two forks C, hinged to the cross-bars c , and connected by the toggle-joint lever f g , having the loop or guide o , working in the vertical groove t , of the slotted standard A, substantially as shown and described.

WILLIAM H. T. TOMLIN.
